UNITED STATES PATENT OFFICE

THOMAS F. CAVANAGH, OF NEW YORK, N. Y.

RECEPTACLE HOLDER

Application filed May 9, 1927. Serial No. 189,920.

This invention relates to receptacle holders.

An important object of the invention is to provide a simple and effective means for detachably anchoring an ash receptacle to a support such as the corner of a table or the like.

Other objects and advantages of the invention will become apparent from the following description, taken in connection with the accompanying drawings in which—

Figure 1 is a perspective view showing the holder attached to the corner of a table and an ash receptacle detachably secured to the holder. Figure 2 is a view looking in the direction of arrow A in Figure 1 and showing the receptacle in section and the holder partly in section and partly in elevation. Figure 3 is a horizontal sectional view taken on the line 3—3 of Figure 2. Figure 4 is a plan view of the holder extended in flat position and with the ash receptacle attached thereto.

Referring to the drawings, the holder is shown applied to the corner of a support, such as a card table 5, having its legs, one of which is indicated by the numeral 6, located adjacent the respective corners of the table top.

The holder is preferably constructed from leather, although other flexible materials may be employed if desired, and includes an envelope-like base 7 which is produced by folding the leather or other flexible material back upon itself and then stitching together the corresponding edges of the two folds 8 as shown at 9, the stitching terminating at opposite ends at the line of fold 10. By thus stitching together the edges of the folded portions 8, which may be cut away as shown, 40 thus providing beveled corners 12, a pocket is formed, in which pocket is secured a flat stiffening member 14, preferably of metal, which is placed within the folds 8 before they are stitched together.

The stiffening member 14 is in the shape of a right triangle and is so arranged that its hypotenuse is parallel with the line of fold 10 and its two other sides are parallel to and spaced an appreciable distance from the beveled corners 12, thus leaving two unstiffened

portions of the base to serve as ears 16 which are adapted to be turned down over and in some instances (as shown) slightly under the edges of the table where they are held by straps 17 which are adapted to embrace a leg 55 6 of the table one strap being passed around the leg in one direction and the other in the opposite direction. These straps 17 are attached to the base 7 at the beveled corners 12 thereof by the stitching 9, the inner ends of 60 the straps being overlapped by said corners.

Suitable means are provided for fastening the straps 17 together about the table leg, such means being herein shown as including a ball member 18 carried by one of the straps and adapted to snap into locking engagement with any one of a plurality of socket members 19 carried by the other strap, the several socket members 19 being provided in order that the effective lengths of the straps may be varied to meet varying conditions such as various thicknesses of table tops and various sizes of table legs, and various positions of table legs with respect to the corners of the table. 75

The ash receptacle 20 is adapted to be detachably connected to the base 7 by suitable means, such as a fastener of the ball and socket type, the socket member 21 being secured to the bottom of the receptacle and the ball member 22 of the fastener being carried by the upper fold 8 of the base 7. As a result of providing a separable fastener as a means for connecting the ash receptacle 20 to the base 10, the ash receptacle may be readily removed from the support 7 without requiring that the holder be detached from its position on the table when it is desired to empty the receptacle of its contents. 80 85

The holder herein shown is neat and attractive in appearance and is securely held in place. The stiff portion of the base resists all efforts to which it may in use be subjected to brush it off or push it off the corner of the table. Again the ash receptacle 20 is relatively rigid with respect to the holder although detachably connected thereto so danger of accidental upsetting or other undue displacement of the ash receptacle is obviated. In addition to these desirable features, the de- 90 95 100

vice may be applied to a highly finished or polished table without danger of marring or otherwise disfiguring its appearance, since the structure is such that only such portions or parts thereof as are constructed from soft, pliant material, such as leather, can come in contact with the table.

5 It will be understood that changes and modifications may be made in the construction shown and above particularly described, without departing from the spirit of the invention as defined in the following claims.

10 What is claimed is:

1. A receptacle holder adapted to be applied to the surface of a table comprising a base of pliable material adapted for engagement with the top of the table, a stiffening member associating with said base for rendering the base rigid, and fastening means 15 cooperating with said base and said table for holding said base down in a flat condition upon the surface of the table.

2. A receptacle holder adapted to be applied to the surface of a table at the corner thereof comprising a base of flexible material 25 having a stiff portion adapted for engagement with the top of the table at the corner thereof and having flexible portions adjacent said stiff portion, said flexible portions being 30 adapted to be folded down about the corner of the table into close engagement therewith, and fastening means secured to said flexible portions and adapted to cooperate with said base and said flexible portions and a part of 35 the table for holding the base down in a flat condition on the surface of the table and for holding said flexible portions in close engagement with adjacent corners of the table.

3. A receptacle holder adapted to be applied to the corner of a table comprising a 40 base of pliable material adapted for engagement with the top of the table, a stiffening member associated with said base for rendering the base rigid, and a pair of straps adapted to embrace a part of the table and cooperate with said base for holding said base down in a flat condition on the surface of the table.

4. A receptacle holder adapted to be applied to the corner of a table and comprising 50 a base of flexible material, a stiffening member housed within said base whereby said base is maintained in a flat and rigid condition, and means adapted to cooperate with a part of the table and with said base for holding said base down upon the surface of the table.

5. A receptacle holder adapted to be applied to the corner of a table and comprising 60 a base of flexible material, a stiffening member housed within said base whereby said base is maintained in a flat and rigid condition, and flexible means adapted to embrace a part of the table and cooperate with such 65 part and with said base for holding the latter

down upon the surface of the table in a flat condition.

6. A receptacle holder adapted to be applied to the corner of a table and comprising an envelope-like base, a stiffening member housed within said base and reinforcing only a portion of said base against flexing and leaving adjacent portions of said base in an unreinforced condition, fastening means secured to the unreinforced portions of said base and adapted to cooperate with a part of the table and said base for retaining the reinforced portion of said base in a flat condition upon the face of the table.

7. A receptacle holder adapted to be applied to the corner of a table and comprising a stiffening member, an envelope-like base housing said stiffening member and having a portion reinforced by said stiffening member and having portions serving as ears 80 adapted to be folded down over the edges of the table, and flexible fastening elements secured to said ears and adapted to cooperate with a part of the table and with the reinforced portion of said base to hold the reinforced portion of said base down upon the surface of the table.

25 In testimony whereof, I have affixed my signature to this specification.
